(No Model.)

J. H. MONTGOMERY.

HOISTING APPARATUS.

No. 296,433.

Patented Apr. 8, 1884.

UNITED STATES PATENT OFFICE.

JAMES H. MONTGOMERY, OF DENVER, COLORADO.

HOISTING APPARATUS.

SPECIFICATION forming part of Letters Patent No. 296,433, dated April 8, 1884.

Application filed December 21, 1883. (No model.)

To all whom it may concern:

Be it known that I, JAS. H. MONTGOMERY, a citizen of the United States, residing at Denver city, in the county of Arapahoe and State 5 of Colorado, have invented certain new and useful Improvements in Hoisting Apparatus, of which the following is a specification, reference being had therein to the accompanying drawings.

10 My invention relates to improvements in hoisting apparatus, in which a whim is actuated by horse-power; and the objects of my invention are, first, to provide a separable drum that may be easily transported; second, 15 to provide a positive lock whereby the weight may be prevented from descending in case of breakage of the machinery, and to provide a convenient means for operating the same. These objects I attain by the use of the device 20 illustrated in the accompanying drawings, forming part of this specification, in which—

Figure 1 is a top view of the entire machine. Fig. 2 is a vertical section of a part of the machine on the line *d c* of Fig. 1; Fig. 3, a detail 25 of the locking device; Fig. 4, a detail of the ratchet and hub; Fig. 5, a detail of ratchet and thimble.

Similar letters refer to similar parts throughout the several views.

30 The timbers *A* and *A'*, having the timbers *B* and *B'* attached thereto, and the timber *a* and hangers *b* constitute the frame-work of the machine.

In the hangers *b* turns the shaft *D*, carrying a drum-wheel, *E*. A hub, *d*, on the shaft *D* is connected by a clutch, *d'*, to a thimble, *g'*. To the latter is secured one end of an arm or sweep, *G*, to the opposite end of which is attached a single-tree, for the purpose of 40 attaching a horse.

The drum-wheel *E* is constructed with a view to taking the same apart to be transported through mountainous countries. I prefer to carry out this feature of my invention in 45 the manner shown in Figs. 1 and 2, where it will be seen that two hub-plates, *e e*, having square holes through their centers, are mounted on the shaft *D*, and retained at a proper distance from each other by the use of hollow 50 distance-washers *f f*, through which bolts *j* pass, as well as through corresponding holes

in the hub-plates *e e*. The bolts *j* are provided with nuts on their ends, which, when screwed into place, compress the hub-plates *e* onto the ends of the distance-washers *f*, binding them securely together. Between the arms *I* are placed distance-washers *c*, and are retained in place by means of bolts *j*, which pass through the arms *I*, and through the washers *c*, and being provided with nuts the arms are 60 drawn tight onto the ends of the distance-washers *c* and retained in that position. A plate, *H*, extends around the distance-washers *c* of sufficient width to form a drum upon which to wind a rope or cable. The arms *I* extend beyond the plate *H* some distance, and are provided with circular bands *h*, made of angle-iron, which form flanges of sufficient 65 depth to admit of the necessary amount of rope or cable being wound thereon. The bands *h* are secured to the ends of the arms *I* by rivets *i* or equivalent means. A brake-beam, *K*, having attached thereto a brake-block, *K'*, is pivoted at one end to the frame-work at *L*, the opposite end of which slides in a slot made 70 in the timber *A'*, and is operated by a rope, *l*, extending to the lever *m*, which is pivoted to the sill *M*. A lip on the side of the lever *m* engages with the ratchet *N* to retain the 75 brake in contact with the drum-wheel *E*. The top part of the hub *d* is serrated in such a manner as to form a ratchet or clutch. The 80 lower end of the thimble *g'* is serrated to correspond with the serrations in the hub *d*, which lock together for the purpose of turning the 85 wheel *E*. The thimble *g'* is provided with a flange, *O*, under which the forked end of a lever, *P*, projects for the purpose of raising the thimble, carrying the sweep *G* out of gear. The lever *P* is fulcrumed at *P'*, and has a rope, 90 *R*, attached to the end thereof at *r*, which extends to the hand-lever *n*. The rope *R* in its course passes around a pulley, *r'*, situated on the frame at *r''*, directly under the outer end of the lever *P*, which enables the rope, when 95 operated by the lever *n*, to draw downward the end of the lever *P*, which raises the thimble *g'* out of connection with the hub *d*.

In order to prevent the drum-wheel *E* from turning backward in the event of the breaking or disarrangement of any part of the before-described machinery, I provide a roller-

lock by affixing to a brake-shoe, F, a roller, S, by means of lugs *t* *t* and the bolt S'. To one end of the brake-shoe F is attached a spring, U, having a tendency to draw the brake-shoe 5 in the direction that the drum-wheel revolves when lowering the bucket. To the opposite end of the brake-shoe is attached a cord or rope, V', which extends to a foot-lever, V, situated at the derrick, which, when retained in the position represented in Fig. 1, holds the brake-shoe forward out of contact with a wedge-shaped piece of wood or metal, W, which is attached to the frame by use of bolts X X, which retain it in such a position relative to the drum-wheel as to form a wedge-shaped opening, in 10 which the lock is forced upon releasing the lever V by the tension of the spring U and the contact of the wheel E in such a manner as to prevent the drum-wheel from turning backward and lowering the weight.

Having thus fully set forth the construction and operation of my invention, what I claim as new, and desire to secure by Letters Patent, is—

- 25 1. The hereinbefore-described hoisting apparatus, consisting, substantially, of a framework, the drum-wheel attached thereto, upon which to wind and unwind a hoisting-rope, a friction-brake, rope, and lever for regulating 30 the descent of the weight, an adjustable arm for the purpose of revolving the drum-wheel, mechanism for disengaging the arm from the drum-wheel, and a lock whereby the weight is prevented from lowering, all operating as 35 described and specified.
2. The drum-wheel B, composed, substantially, of the shaft D, the flanges e, having slots e' made therein, arms I, the distance-washers f and e, the band H, the rims h, and the bolts 40 *j* and *j'*.

3. In a hoisting apparatus, the combination, with the drum-wheel E and shaft D, of the hub *d*, the thimble *g*, and sweep G, whereby force applied to the arm revolves the drum-wheel.

4. In a hoisting apparatus, the combination, with the drum-wheel E, the shaft D, the hub *d*, and thimble *g*, of the lever P, fulcrumed to the frame, and having the rope R attached to the end thereof, the pulley *r*, and hand-lever *n*, whereby the sweep is thrown out of gear.

5. In a hoisting apparatus, the combination, with the drum-wheel E, of the brake-block K', brake-lever K, the rope *l*', the hand-lever *m*, and ratchet N, all operating as specified.

6. A roller-lock consisting, substantially, of a brake-shoe, F, having lugs *t* thereon, and the roller S.

7. In a hoisting apparatus, the combination of the roller-lock, consisting of the brake-shoe F, having lugs *t* thereon, carrying the roller S, the sloping block W, spring U, the cord V', and the foot-lever V, all operating as described.

8. In a hoisting apparatus, the combination of a drum or wheel, the roller-lock, composed of the brake-shoe F, the roller S, and tapering wedge W, all operating as specified.

9. The forked lever P, fulcrumed at P', whereby the thimble is disengaged from the drum-wheel.

In testimony whereof I affix my signature in presence of two witnesses.

JAMES H. MONTGOMERY.
